Louis Steinberger INVENTOR
BY
Constance C. Billing
her ATTORNEY

UNITED STATES PATENT OFFICE.

LOUIS STEINBERGER, OF BROOKLYN, NEW YORK.

INSULATOR-SUPPORTING PIN.

Application filed November 6, 1918. Serial No. 261,432.

To all whom it may concern:

Be it known that I, LOUIS STEINBERGER, a citizen of the United States, and a resident of the borough of Brooklyn, city and State 5 of New York, have invented certain new and useful Improvements in Insulator-Supporting Pins, of which the following is a specification.

This invention relates to a pin for supporting pin type line insulators.

One of the objects of the invention is to provide a flexible pin with which to support an insulator.

Another object is to provide an improved 15 flexible and springy support for a pin type insulating body.

Another object of the invention is to provide a supporting pin which has a coiled formation at one end for attachment to a 20 body of insulating material which end is flexible and springy and a rigid portion at the other end for attachment to a support.

Another object of the invention is to form the portion of the supporting pin, which is 25 ordinarily screw threaded for attachment to the insulator into a coiled spring so that the same will act as though it were screw threaded at the point of attachment to the insulating body.

Other objects will appear from the subjoined specification and claims.

In the drawings, Fig. 1 is a vertical view showing the insulator portion in section and the pin supporting portion in elevation.

Fig. 2 is a perspective view of a spring supporting pin.

It has been found from experience that when a rigid pin is used for supporting the insulating body of a pin type insulator that 40 the body is likely to be destroyed when subjected to blows or to mechanical strains. This disadvantageous result is due to the fact that there is no "give" to the structure as a whole when subjected to such blows or 45 strains, as the pin and insulating body are rigidly connected together.

Various means have been adopted to overcome this disadvantage and thus make a practical device. One of the means adopted 50 to this end is to place a layer of lead between the upper portion of the pin and the body of insulating material which tends to afford a cushioning effect. Another means for accomplishing a similar result has been to secure 55 pieces of wood to the metal portion of the pin and to form screw threads in the

wood by means of which the insulator body is secured to the pin. Such a structure had a certain cushioning action when strains were brought upon the insulator body by 60 blows or otherwise.

I have found that the necessary results will be produced in an efficient manner by making the supporting pin flexible and springy. In order to connect such a supporting pin to the body of insulating material the tapering end of the pin is coiled into the shape of a helical spring, then the spring portion of the pin not only remains flexible but is of such form that it will act 65 like a screw-threaded projection for the purpose of securing the insulator body thereto as shown.

A special feature of the invention, therefore, consists in a tapering pin structure in 75 which the portion of smallest cross section which is secured to the insulator body for supporting the same is flexible and springy.

Referring to the drawings, in which like reference characters indicate the same parts 80 in the several views:

The insulator body 10 is made of any suitable insulating material, preferably that material known in the art as "electrose," and it is molded into any suitable form, one of 85 the forms being illustrated in Fig. 1.

A centrally disposed conically shaped or tapering cavity 11 is formed in the said body of insulating material and it is provided with screw threads 12 in the wall thereof. 90 A supporting pin 20, made of any suitable material, preferably of metal, is provided with a flexible or springy tapering end at 21, which end is coiled into the shape of a spiral and tapering spring 22, the coils of 95 the spring being utilized as a screw by means of which the pin is screwed into the screw threads 12 of the centrally disposed cavity 11 of the insulator body 10. The pin 20 may be mounted in position upon the support 8 and secured thereto by a lock nut 30 on the projecting lower end of the pin on the under side of the support, as shown. In securing the pin 20 to the cross arm the lower projecting end thereof is passed 105 through a hole 31 in the same and a washer 32 may be placed underneath the cross arm and held in place by the nut 30, all as well known in this art. When the pin is thus secured, the insulator body may be screwed 110 into place on the coil portion of the pin.

As stated above, the threaded part of the

insulator supporting pin is usually tapered slightly for the purpose of more readily attaching and detaching the same from the conical core of the insulator body.

5 In constructing my supporting pin I reduce the diameter of the same in such a manner as to practically make it a spring at its extremity.

As has been heretofore set forth, the ultimate object of the invention is to provide a supporting pin for an insulating body of pin type, the pin being of such a flexible and springy character that the insulator body will move with the pin when subjected to 10 mechanical stresses and strains by the force of the wind or by pulls or blows. The effect of such strains upon the insulator will thus be greatly minimized and the insulator body will thus be prevented from breaking down 15 and from being destroyed.

As shown, the insulator body 10 is provided with a pair of tapering flanges or petticoats 40 and 41, and at the upper portion of the body is the usual groove or channel 50 to form a seat for the reception of the line wire (not shown) and a groove or channel 51 into which a tie wire (not shown) is fitted to hold the line wire in place upon the insulator.

20 As many changes of construction could be made within the scope of my invention, it is intended that all matter contained in the above description or shown in the accompanying drawings shall be interpreted as 25 illustrative and not in a limiting sense.

Having now described my invention what I claim as new and desire to secure by Letters Patent is:

1. In a device of the class described, a 30 tapered pin for supporting an insulator body, said pin being tapered at one end, and formed by bending into a spring formation at its tapered end, said formation being integral.

40 2. In a device of the kind described, a supporting pin for a pin type insulator the lower portion of the pin being rigid, the up-

per portion of the pin being springy and formed by bending into a helical tapered coil the said portions being integral.

45 3. In a device of the kind described, a supporting pin for a pin type insulator, the lower portion of the pin being rigid and the upper portion of the pin being formed by bending into a helical tapered coil, the said 50 tapered coil being flexible and springy to bend to any side of the axis of the lower rigid portion and being integral with said portion.

55 4. As an article of manufacture, an insulator supporting pin, the upper portion of said pin being formed into a tapering helical coil by bending, the coil portion being flexible and springy for bodily movement and the lower portion of said pin being fixed 60 and rigid, the structure being integral.

65 5. As an article of manufacture, an insulator supporting pin of tapered form, the end having the largest cross section being rigid and the end having the smallest cross 70 section being bendable and springy, the said bendable springy end being shaped by bending into a helical tapered coil to form screw-threads, the structure being integral.

75 6. An insulator supporting pin of tapered form, the end having the largest cross section being rigid and the end having the smallest cross section being bendable and springy, the said bendable springy end being shaped by bending into a helical tapered 80 coil to form screwthreads, in combination with an insulator body provided with a tapered cavity the wall of which is screw-threaded and in engagement with the turns of the springy helical coil, the pin structure 85 being integral.

90 In witness whereof I have hereunto set my hand at the borough of Manhattan, city and State of New York, this 23 day of October, 1918.

LOUIS STEINBERGER.

In presence of—

ZITA M. GRAHAM.
